UNITED STATES PATENT OFFICE

WILLIAM R. RESPES, OF GRASSMERE, STATEN ISLAND, NEW YORK, ASSIGNOR TO
NAZ-DAR COMPANY, OF CHICAGO, ILLINOIS, A CORPORATION OF ILLINOIS

STENCILING MACHINE

Application filed June 14, 1930. Serial No. 461,229.

This invention relates to the art of printing and particularly to an improved form of stenciling machine which is adapted to the printing of designs in one or more colors 5 on paper, cardboard, or other material which can be made in sheet form.

In stenciling machines which have heretofore been designed for work of this nature, the printing is usually effected by superposing a stencil of silk cloth or other suitable material upon the sheet to be printed and then rubbing a body of paint over the stencil by means of a wiper or squeegee to force the paint through the porous or penetrable 15 areas of the stencil. The squeegee is mounted for reciprocatory movement, it being moved over the stencil in one direction to print a sheet and in the reverse direction to print the next succeeding sheet. Before reversing the movement of the squeegee it is 20 raised from the stencil by suitable mechanism and is then shifted or jumped over the batch of paint. The squeegee is then lowered back onto the stencil preparatory to movement in the opposite direction across the stencil.

An important object of my invention is to provide mechanism for controlling the movement of the squeegee in such a manner as to avoid the necessity of lifting it over the batch of paint to effect the printing of successive sheets. The mechanism is designed to move the squeegee in an endless path so that it always moves across the stencil sheet in the same direction during the printing operation. By eliminating this shifting or jumping of the squeegee over the batch of paint, I am able to obtain a greatly improved quality of work.

Another object of the invention is to provide a stenciling machine of the character set forth which is adapted for automatic operation so as to permit continuous printing of the sheets as they are fed under the printing unit.

Further objects and advantages of the invention will be apparent as I proceed with my specification, which, taken in connection with the accompanying drawings, discloses 50 a preferred embodiment thereof.

Referring to the drawings:

Fig. 1 is a side elevational view of the stenciling machine;

Fig. 2 is a top plan view of the same;

Fig. 3 is a broken plan view of the bed 55 plate with the printing frame removed therefrom;

Fig. 4 is a vertical longitudinal section through the printing frame and bed plate, 60 taken on the line 4-4 of Fig. 2;

Fig. 5 is a broken transverse section through the printing frame and bed plate taken on the line 5-5 of Fig. 1;

Fig. 6 is a detail view illustrating the off-set chain drive and sprocket wheel mechanism; and

Fig. 7 is a detail section through the squeegee.

Referring to the drawings, and particularly to Figs. 1 and 2, the machine comprises 70 a supporting frame indicated generally by the numeral 10; sheet feeding mechanism 11 supported on the frame 10; and a printing unit 12 for stenciling designs in one or more colors as the sheets 13 of cardboard or other suitable material are fed thereto by the feeding mechanism 11.

The supporting frame 10 consists of four vertical post members 14, which are tied together near their lower ends by crossbars 80 15, and a horizontal bed plate supporting unit consisting of a pair of beams 16 which are supported on the upper ends of the posts 14. A series of tie bars 17 extending between the posts 14 and the bars 16 afford 85 additional support for the projecting ends of the bars 16, and stiffening rods 18 are provided to connect the center portions of the bars 17 with the upper ends of the posts 14. It will be understood that these frame members are connected together by suitable bolts or rivets to form a rigid frame unit.

The sheet feeding mechanism 11 consists of a bed plate 19 which rests on the longitudinal bars 16, and an endless feed belt 21 95 which takes over rollers or drums 22 and 23 carried on spindles which are journaled in the ends of the longitudinal frame members 16. The bed plate 19 may be considered as consisting of three sections, the first section 100

24 being the feed section, the middle section 25 being considered as the printing section, and the section 26 being considered as the discharge section from which the sheets are 5 delivered to suitable drying trays. The feed belt 21 is driven from a motor 27 which is suitably supported on the crossbars 15 of the supporting frame 10. A main drive shaft 28, journaled at its opposite ends in a 10 pair of uprights 29, is driven from the motor 27 through a sprocket wheel 30 and a chain 31 which takes over the wheel 30 and a second sprocket wheel 32 carried by the armature shaft of the motor 27. Power is 15 taken from the drive shaft 28 to the conveyor belt roller 22 through an offset drive chain 33 which takes over a pair of sprocket wheels 34 and 35 on the shaft 28 and a corresponding pair of sprocket wheels 36 and 37 on the projecting end of a spindle 38 carrying the roller 22. The sprockets 34 and 35 are both drive sprockets and are keyed to the shaft 28. The sprocket 36 is a drive sprocket and is keyed to the spindle 38. 20 The sprocket 37, however, is an idler sprocket which engages the offset run of the chain 33 to temporarily stop movement of the conveyor belt 21 during the printing operation.

30 The offset chain arrangement for obtaining intermittent driving motion, such as that just described in connection with the feed belt roller 22, is illustrated in Fig. 6. The chain 33 is made up of alternately offset portions 39 and 41, the portions 41 engaging the drive sprockets 34 and 36, and the portions 39 engaging the drive sprocket 35 and the idler sprocket 37. During the interval in which the offset portion 39 is taking over the 35 idler sprocket 37, the feed belt roller 22 remains stationary. As will presently appear, it is during this period that the printing of the sheet occurs.

Referring to Figs. 1, 4 and 5, the printing 45 unit 12 which is disposed over the central section 25 of the bed plate 19 comprises a printing frame 42, a squeegee 43 which is movably supported in the frame 42; a stencil 44 disposed in the frame 42 below the 50 squeegee 43; and a paint supply unit 45 for feeding paint onto the stencil 44.

The printing frame 42 consists of three main parts, namely, an upper part 46 which may be termed a squeegee box, a lower base 55 portion 47 which, as will presently appear, rests on movable supports carried by the frame members 16, and a stencil frame 48 which is interposed between the squeegee box 46 and the base portion 47. The squeegee box 46 is rectangular in shape and consists of side walls 49 and end walls 51 which are bound together at their upper marginal edges by angle bars 52 to form a rigid box unit. A pair of angle bar irons 56 extend longitudinally along the side walls

49, the lower edges of these bars resting on the base portion 47 to afford a support for the squeegee box. In the embodiment shown a pair of stiffening plates 54 are provided to afford additional support for the squeegee box. The base portion 47 of the printing frame consists of a pair of U-shaped channel irons 55 which are positioned to open upwardly, as indicated in Fig. 5, to engage the lower edges of the bars 53 and 54. 70 The stencil frame 48 is made up of a pair of side bars 56 and a pair of end bars 57 which are bound together at their corners to form a rigid frame unit. The stencil 44, which is ordinarily a sheet of finely woven silk cloth, is tacked along its edges to a rectangular wooden frame 58 which is connected by bolts or other suitable means to the stencil frame 48. The division of the printing frame 42 into these three separate units provides means for easy removal and replacement of the stencil frame 48 carrying the stencil 44. The squeegee box 51 merely has to be lifted upwardly to be removed, whereupon the stencil frame 48 may be lifted from the base portion 47. This feature is a highly practical one inasmuch as the stencils have to be frequently removed for cleaning or replacement by stencils of other designs. 80

Referring particularly to Figs. 4, 5 and 7, the squeegee 43 is suspended in the printing frame 42 between a pair of endless carrier chains 59 which take over corresponding pairs of sprocket wheels 61 carried by shafts 62 which are journaled at their opposite ends in the side walls 49 of the squeegee box. The squeegee 43 consists of a wood or metal bar 63 which is provided at its opposite ends with attaching brackets 64 (Fig. 105 5) to afford connection with the chains 59. The lower front face of the bar 63 is provided with a rubber squeegee element 65 which is adjustably attached to the bar 63 as by a screw 66 extending through an adjusting slot 67 in the squeegee element 65. The pressure of the squeegee element 65 on the stencil 44 can be varied by loosening the screw 66 and shifting the element 65 relative to the bar 63. The front face of the bar 63 is provided with a metal guard plate 68 which extends across the entire width of the squeegee. The opposite ends of the bar 63 are bent inwardly as indicated at 70 to close the ends of the trough formed by said bar and the squeegee element 65. A rubber strip 69 is attached to the lower front edge of the guard plate 68. The end walls 51 of the squeegee box are provided with curved 115 aprons 71 and 72 for preventing the escape of paint from the squeegee when it is raised from the stencil 44. The side walls 49 of the squeegee box are provided between the sprocket wheel 61 with angle bars 73 (Fig. 120 65

5) which support the upper and lower runs of the chains 59.

Referring to Figs. 1 and 4, the paint supply unit 45 in the embodiment shown consists of a supply tank 74 which is supported by a pipe 75 carried by the squeegee box 46. A supporting block 76 carried by the end wall 51 of the squeegee box supports the lower end of the pipe 75. The block 76 is 10 provided with a duct 77 communicating with the pipe 75. A curved block 78 is bolted to the inner face of the end wall 51 and is, in turn, provided with a duct which communicates through the wall 51 to the duct 77. 15 The paint is supplied through this fluid path to the apron 72 from which point it is wiped or moved by the squeegee down onto the stencil 44. A needle valve 80 extends into the duct 77 and affords means for controlling the paint flow from the supply tank 74.

The path of movement of the squeegee 43 will be apparent from Fig. 4. As the carrier chains 59 move in a clockwise direction 25 over the sprockets 61 the squeegee 43 moves a batch of paint 79 across the stencil 44 in the direction from right to left. As the paint moves over the stencil it is forced through the penetrable areas to form the 30 design on the cardboard sheet 13 which rests on the bed plate 19 with its upper surface in contact with the stencil 44. After the squeegee has completed its movement across the cardboard sheet it carries the 35 batch of paint 79 upwardly against the apron 71 and as it proceeds across the top run of the chain any unused paint is carried in the trough-shaped container formed by the guard plate 68 and the rubber squeegee 40 element 65. As the squeegee approaches the end of the top run it is again turned downwardly and carries with it the unused portion of the batch of paint 79 and any additional paint which is supplied from the tank 45 74. The strip 69 and the apron 72 prevent the escape of the paint as the squeegee approaches this downturned position preparatory to movement across the next sheet of cardboard. 50 The printing frame 42 is mounted for vertical reciprocatory movement on the bed plate 19 so as to permit the feeding in of the fresh sheets and the withdrawal of the printed sheets, thus providing for continuous printing. The mechanism for raising and lowering the printing frame 42 consists of a pair of cam shafts 81 and 82, journaled at their opposite ends in the longitudinal frame members 16, and provided, respectively, with pairs of cam discs 83 and 84 for engaging against the lower faces of the U-shaped channel bars 55 forming the base portion of the printing frame 42. The projecting end of the cam shaft 81 is provided 55 with a pair of sprocket wheels 85 and 86, and the cam shaft 82 is similarly provided with a pair of corresponding sprocket wheels 87 and 88. Intermittent turning of the cam shafts 81 and 82 is accomplished by the use of an offset chain 89 consisting of alternate offset portions 91 and 92. The sprockets 86 and 88 are idler sprockets so that when the offset portions 91 are in engagement therewith no turning of the cam shafts 81 and 82 is produced. The sprockets 85 and 87 are keyed to the corresponding cam shafts 81 and 82 to effect turning thereof when the offset chain portions 92 are in engagement with these sprocket wheels. It will be apparent that as the cam discs 83 and 84 are turned they will, through cam action against the bars 55, raise and lower the printing frame 42 to permit the introduction and removal of the sheet stock from the middle section 25 of the bed plate 19. As the printing frame 42 is raised the stencil 44 is lifted from the printed sheet and, as will presently appear, the timing of the conveyor belt 21 is such as to remove the printed sheet and introduce a fresh sheet under the printing frame before the same is lowered back into printing position for the next printing operation. The cam discs 83 are given a slight lead over the cam discs 84 so as to lift the printing frame 42 by a 95 tilting movement. This tilting movement is repeated in reverse manner when the printing frame is lowered to replace the stencil on the cardboard sheet. The object of this tilting movement is to separate the stencil from the cardboard sheet in a progressive manner approximating a peeling action rather than by a sudden removal over the entire area of the sheet. The chain 89 takes over a small sprocket wheel 93 which is carried on a stub shaft journaled in the upright 29. The sprocket 93 is driven from the main drive shaft 28 through reduction gears 94 and 95. The sprocket 93 is really a double sprocket so as to engage either of the offset portions 91 and 92 of the chain 89. Referring to Figs. 3-5, the central section 25 of the bed plate 19 is provided with dowel pins 96 for keeping the printing frame 42 in aligned position on the bed plate. These pins extend through aligned apertures in the channel bars 55 and the stencil frame 48. These openings are sufficiently large so that the tilting movement given to the frame by the cam discs does not cause a binding action. The printing frame 42 is also provided with aligning fingers 97 which engage the edge of the cardboard sheet to hold it in position during the printing operation. When the printing frame is lowered onto the bed plate these fingers pass through corresponding apertures 98 in the feed belt 21 and aligned apertures 99 in the bed plate 19. The aligned fingers 97 which are carried by the plates 53 and 54 of the printing frame may be provided with 100 105 110 115 120 125 130

adjusting screws as indicated at 101 to take care of any variation in width of the sheet stock. The channel bars 55 are provided with spring fingers 102 (Fig. 5) which engage the opposite edges of the cardboard sheet when the printing frame is in the lowered position. When the frame is raised these fingers hold the sheet against the carrier belt 21 while the stencil is being lifted off. After the frame has been raised enough to straighten out these fingers they are, in turn, lifted from the sheet which may then be withdrawn by the belt 21.

Referring to Figs. 1, 3 and 5, the squeegee carrier chains 59 are driven by a sprocket wheel 103 carried by a stub shaft journaled in the side wall 54 of the squeegee box. The upper teeth of this sprocket mesh with a sprocket chain 104 which takes over a pair of sprocket wheels 105 carried by the projecting ends of the shafts 62. The lower teeth of the sprocket 103 mesh with a sprocket chain 106 which takes over a pair of idler sprockets 107 and 108 carried by the cam shafts 81 and 82, respectively. The chain 106 also takes over a sprocket wheel 109 which is secured to the main drive shaft 28. When the printing frame 42 is lowered into printing position the sprocket wheel 103 engages the drive chain 106 and is turned to move the squeegee in an endless path described by the carrier chains 59.

The timing of the various parts of the mechanism is obtained in accordance with the ratio of the various sprocket drive wheels and by the relative lengths of the offset portions of the drive chains 33 and 89. These relative adjustments must be such that the raising and lowering of the printing frame 42 will occur in timed sequence with the movement of the feed belt 21. The timing must also be adjusted so that the squeegee will be given a full movement from one edge of the stencil to the other while the printing frame is in the printing position. In the embodiment shown in the drawings the size of the sprocket drive wheel 36 which controls the movement of the conveyor belt 21 is such that about three revolutions are required to move a cardboard sheet 13 across the printing section 25 of the bed plate 19. Therefore, the length of the offset portion 41 of the chain 33 will be equal to about three times the circumference of the sprocket wheel 36. In the case of the drive chain 89, which controls the movement of the cam discs 83 and 84, the offsets in the chain will be equal in length to the circumference of the sprocket wheels 85 and 87 inasmuch as the printing frame is raised and lowered once for each revolution of the cam shafts 81 and 82. Moreover since the cam discs 83 and 84 are turned simultaneously the positioning of the offsets in the chain 89 must be such that both of the drive sprockets 85 and 87 are

working at the same time and so that both the idler sprockets 86 and 88 are working at the same time. Since both the feed belt chain 33 and the cam drive chain 89 are driven from the drive shaft 28 it is necessary to employ the reduction gears 94 and 95 to slow down the speed of the chain 89. This reduction gives the desired effect of obtaining one cycle of raising and lowering of the printing frame 42 during the interval of removal of the printed sheet and introduction of a fresh sheet by the conveyor belt 21. It is further to be noted that with the system of driving mechanism shown the squeegee 43 will have to make a complete revolution while the printing frame is lowered into printing position inasmuch as in the raised position of the printing frame the squeegee remains stationary. The necessary speed for this movement is obtained by adjusting the size of the sprocket wheel 109 which engages the chain 106. Since the sprocket wheels 107 and 108 are mounted for free rotation on the cam shafts 81 and 82 the movement of the chain 106 does not interfere with the movement of the cam drive chain 89.

It is believed that a brief outline of the several steps occurring in the operation of the machine will aid to a clearer understanding of the invention. Assuming that the printing of a sheet has just been completed, at which point the squeegee 43 will be in the upturned position on the top run of the carrier chains 59, the offset portions 92 of the cam drive chain 89 move into engagement with the sprockets 85 and 87 to turn the cam discs 83 and 84. Turning of these cam discs raises the printing frame 42 to remove the stencil 44 from the printed sheet 13. Immediately upon the removal of the stencil from the printed sheet, the offset portion 41 of the carrier belt drive chain 33 engages the sprocket 36 to start movement of the feed belt 21. While the printing frame is in the raised position the printed sheet is moved by the belt 21 from the middle section 25 of the bed plate 19 to the discharge section 26 of the bed plate. A fresh sheet is fed from the feed section 24 to the printing section 25 simultaneously with the withdrawal of the printed sheet. By the time the fresh sheet is positioned below the printing frame the offset section 39 of the chain 33 has moved into engagement with the idler sprocket 87 to stop movement of the feed belt 21. Immediately upon the bringing of the fresh sheet to a position of rest, the printing frame 42 is lowered by the cam discs 83 and 84 to bring the stencil 44 into engagement with the upper face of the sheet 13. As soon as the printing frame is in the lowered position the offset portions 91 of the cam drive chain 89 move into engagement with the idler sprockets 86 and 88

to stop turning of the cam discs 83 and 84. The lowering of the printing frame 42 brings the carrier chain drive sprocket 103 into engagement with the chain 106 which moves continuously. During the time the feed belt drive chain 33 and the cam drive chain 89 are inactive the squeegee 43 is carried through one complete run of the carrier chains 59, movement across the lower run of these chains serving to force the paint through the stencil onto the sheet 13. After the passage of the squeegee across the stencil the cycle of operations is repeated, the printing frame 42 being raised by the cam discs 83 and 84 and the feed belt 21 being again rendered active to withdraw the printed sheet and introduce a fresh sheet under the printing frame.

The foregoing detailed description has been given for clearness of understanding only, and no unnecessary limitations should be understood therefrom, but the appended claims should be construed as broadly as permissible in view of the prior art.

25 What I regard as new and desire to secure by Letters Patent is:

1. A stenciling machine for printing sheet stock and the like comprising, a bed plate, a stencil, a stencil supporting frame mounted for free vertical movement relative to said bed plate, a squeegee, including a wiping element for moving a batch of paint over the stencil, and means for advancing the squeegee across the face of the stencil when said frame is in the lowered position on the bed plate, said means being operable to return the squeegee from the forward edge of the stencil along an endless path back into printing position at the rear edge of the stencil preparatory to the printing of the next succeeding sheet.

2. A stenciling machine for printing sheet stock and the like comprising, a bed plate, a stencil, a stencil supporting frame disposed over said bed plate, means for feeding sheet stock into printing position on the bed plate and for removing the printed sheet therefrom, means operating in timed sequence with the feed means for raising and lowering said frame relative to the bed plate, a squeegee, including a wiping element for moving a batch of paint over the stencil, and means for advancing the squeegee across the face of the stencil when said frame is in the lowered position on the bed plate, said means being operable to return the squeegee from the forward edge of the stencil along an endless path back into printing position at the rear edge of the stencil preparatory to the printing of the next succeeding sheet.

3. A stenciling machine for printing sheet stock and the like comprising a bed plate a stencil, a stencil supporting frame mounted for free vertical movement relative to

said bed plate, a squeegee, including a wiping element for moving a batch of paint over the stencil, and means comprising an endless chain conveyor for advancing the squeegee across the face of the stencil when the frame is in the lowered position on the bed plate.

4. A stenciling machine for printing sheet stock and the like comprising a bed plate a stencil, a stencil supporting frame mounted for free vertical movement relative to said bed plate, a squeegee, including a wiping element for moving a batch of paint over the stencil, and an endless chain conveyor for advancing the squeegee across the face of the stencil when said frame is in the lowered position on the bed plate, said conveyor being operable to return the squeegee from the forward edge of the stencil along an endless path back into printing position at the rear edge of the stencil preparatory to the printing of the next succeeding sheet.

5. In a stenciling machine, for printing sheet stock and the like, a bed plate, a stencil, a stencil carrying frame movably supported on said bed plate, cam mechanism for raising and lowering said frame relative to the bed plate, a squeegee, including a wiping element for moving a batch of paint over the stencil, and means for advancing the squeegee across the face of the stencil when said frame is in the lowered position on the bed plate, said means being operable to return the squeegee from the forward edge of the stencil along an endless path into printing position at the rear edge of the stencil preparatory to the printing of the next succeeding sheet.

6. A stenciling machine for printing sheet stock and the like comprising, a bed plate, a stencil, a stencil supporting frame mounted for free vertical movement relative to said bed plate, a squeegee, including a wiping element for moving a batch of paint over the stencil, means for supplying a coloring medium to the stencil, and means for advancing the squeegee across the face of the stencil when said frame is in the lowered position on the bed plate, said means being operable to return the squeegee from the forward edge of the stencil along an endless path back into printing position at the rear edge of the stencil preparatory to the printing of the next succeeding sheet.

7. In a stenciling machine, a bed plate, a stencil, a stencil supporting frame, means for feeding sheet stock into printing position on the bed plate and for removing the printed sheet therefrom, means operating in timed sequence with the feed means for raising said frame to remove the stencil from the printed sheet, said means being operable to lower the frame to bring the stencil into printing position on the next succeeding sheet, and color applying means including

- a squeegee and means for moving the squeegee across the stencil when said frame is in printing position on the bed plate, said last-mentioned means being operative to return 5 the squeegee along an endless path into position for printing the succeeding sheet.
8. In a stenciling machine, a bed plate, a stencil, a stencil supporting frame, means for feeding sheet stock into the printing 10 position on the bed plate and for removing the printed sheets therefrom, means operating in timed sequence with the feed means for raising said frame to remove the stencil from the printed sheet, said means being 15 operable to lower the frame to bring the stencil into printing position on the next succeeding sheet, flexible finger members for holding down the printed sheet during the interval of removal of the stencil therefrom,
- 20 and color applying means including a squeegee and means for moving the squeegee across the stencil when said frame is in printing position on the bed plate.
9. In a stenciling machine, a bed plate, a 25 stencil, a stencil supporting frame; means for feeding sheet stock into printing position on the bed plate and for removing the printed sheets therefrom, means operating in timed sequence with the feed means for 30 raising said frame to remove the stencil from the printed sheet, said means being operable to lower the frame to bring the stencil into printing position on the next succeeding sheet, aligning means for positioning the sheet on the bed plate preparatory to the lowering of the stencil supporting frame thereon, and color applying means including a squeegee and means for moving 35 the squeegee across the stencil when said 40 frame is in printing position on the bed plate, said last-mentioned means being operative to return the squeegee along an endless path into position for printing the succeeding sheet.
- 45 10. A stenciling machine for printing sheet stock and the like comprising, a bed plate, a stencil, a stencil supporting frame, a squeegee, including a wiping element for moving a batch of paint over the stencil, 50 and means for advancing the squeegee across the face of the stencil when said frame is in printing position on the bed plate, said means being operative to return the squeegee from the forward edge of the stencil along 55 an endless path back into printing position at the rear edge of the stencil preparatory to the printing of the next succeeding sheet.
11. In a stenciling machine for printing 60 sheet stock and the like, a printing frame, a stencil supported in said frame, and color applying means comprising an endless conveyor movably supported in the printing frame and a squeegee extending transversely of the frame provided with a wiping element for moving a batch of paint over the
- stencil, said squeegee being movable with said conveyor over the face of the stencil when the frame is in printing position on the sheet stock.
12. In a stenciling machine for printing 70 sheet stock and the like, a printing frame, a stencil supported in said frame, and color applying means comprising an endless conveyor movably supported in the printing frame and a squeegee extending transversely 75 of the frame and movable with said conveyor over the face of the stencil when the frame is in printing position on the sheet stock, said squeegee including a rubber wiping element and a guard member co-operating 80 with said element to form a trough for retaining the coloring medium in the upturned position of the squeegee.
13. A stenciling machine comprising, a bed plate, a printing frame disposed over 85 said bed plate, a stencil supported in said frame, means for raising and lowering the printing frame relative to the bed plate, a squeegee movably supported in said frame and provided with a wiping element for moving a batch of paint over the stencil, and carrier means for moving the squeegee along 90 an endless path in the printing frame, said carrier means operating to advance the squeegee across the face of the stencil when the frame is in the lowered position on the bed plate.
14. A stenciling machine comprising, a bed plate, a printing frame disposed over 95 said bed plate, a stencil supported in said frame, means for raising and lowering the printing frame relative to the bed plate, a squeegee movably supported in said frame and provided with a wiping element for moving a batch of paint over the stencil, and an endless chain conveyor for advancing the squeegee across the face of the stencil when the frame is in the lowered position on the bed plate.
15. In a stenciling machine for printing 100 sheet stock and the like, a bed plate, a printing frame movable relative to said bed plate, a stencil mounted in said frame, a squeegee movably supported in said frame and provided with a wiping element for moving a batch of paint over the stencil, and an endless chain conveyor operable to advance the squeegee across the face of the stencil during 105 the interval of contact between the stencil and the sheet to be printed.
16. A stenciling machine comprising, a bed plate, a printing frame disposed over 110 said bed plate, a stencil supported in said frame, means for feeding sheet stock into printing position on the bed plate and for removing the printed sheets therefrom, means for periodically raising the printing frame to remove the stencil from the printed sheet, said means being operable to lower the frame to bring the stencil into printing 115 position.

- tion on the next succeeding sheet, a squeegee movably supported in said frame and provided with a wiping element for moving a batch of paint over the stencil, and carrier means for moving the squeegee along an endless path in the printing frame, said carrier means operating to advance the squeegee across the face of the stencil when the frame is in the lowered position on the bed plate.
- 10 17. A stenciling machine comprising, a bed plate, a printing frame disposed over said bed plate, a stencil supported in said frame, means for feeding sheet stock into printing position on the bed plate and for removing the printed sheet therefrom, means operating in timed sequence with the feed means for raising the printing frame to remove the stencil from the printed sheet, said means being operable to lower the frame to bring the stencil into printing position on the next succeeding sheet, a squeegee movably supported in said frame, and carrier means for moving the squeegee along an endless path in the printing frame, said carrier means operating to advance the squeegee across the face of the stencil when the frame is in the lowered position on the bed plate.
- 15 18. In a stenciling machine, a bed plate, a printing frame movable relative to said bed plate, a stencil carried in said frame, and color applying means comprising an endless conveyor movably supported in the printing frame and a squeegee supported on said conveyor and provided with a wiping element for moving a batch of paint over the face of the stencil when said frame is in printing position on the bed plate.
- 20 19. In a stenciling machine, a bed plate, a printing frame movable relative to said bed plate, a stencil carried in said frame, and color applying means comprising an endless chain conveyor movably supported in the printing frame and a squeegee extending transversely of the frame and movable with said conveyor over the face of the stencil when the frame is in printing position on the bed plate, said squeegee including a rubber wiping element and a guard member co-operating with said wiping element to form a trough for retaining the coloring medium in the upturned position of the squeegee.
- 25 20. A stenciling machine for printing sheet stock and the like comprising, a bed plate including a feed section, a discharge section, and a printing section intermediate the feed and discharge sections, a printing frame positioned over the printing section of said bed plate, a stencil removably supported in said printing frame, means including a conveyor belt for feeding the sheet stock from the feed section of the bed plate into printing position below the printing frame, said means being further operable to remove the printed stock from the printing section of the bed plate, cam mechanism operating in timed sequence with said feed means for raising the printing frame to remove the stencil from the printed sheet, said mechanism including means for tilting the frame to progressively separate the stencil from the printed sheet, flexible finger members for holding down the printed sheet during the interval of removal of the stencil therefrom, aligning means for positioning the sheet on the bed plate preparatory to the lowering of the printing frame thereon, means for supplying a coloring medium to the stencil, and color applying means comprising an endless chain conveyor removably supported in the printing frame and a squeegee extending transversely of the frame and movable with said conveyor over the face of the stencil when the frame is in the lowered position on the bed plate, said squeegee including a rubber wiping element and guard member co-operating with said wiping element to form a trough for retaining the coloring medium in the upturned position of the squeegee.
- 30 21. In witness whereof, I hereunto subscribe my name to this specification.
